[57] **CLAIM**

The ornamental design for a squeegee, as shown and
described.

DESCRIPTION

FIG. 1 is a perspective view of a squeegee showing my
new design;

FIG. 2 is a top plan view thereof;

FIG. 3 is a front elevational view, the rear elevational
view being a mirror image thereof;

FIG. 4 is an elevational view taken from the left side of
FIG. 3; and,

FIG. 5 is a bottom plan view thereof.

FIG. 1

FIG. 2

FIG. 3

FIG. 4

FIG. 5
